UNITED STATES PATENT OFFICE.

HUGH W. KIMES, OF DAYTON, OHIO, ASSIGNOR TO VAILE & KIMES, A FIRM COMPOSED OF JOHN H. VAILE AND HUGH W. KIMES, OF DAYTON, OHIO.

FLUID-MOTOR.

No. 866,592.

Specification of Letters Patent.

Patented Sept. 17, 1907.

Application filed March 26, 1907. Serial No. 364,718.

To all whom it may concern:

Be it known that I, HUGH W. KIMES, a citizen of the United States, residing at Dayton, in the county of Montgomery and State of Ohio, have invented certain new and useful Improvements in Fluid-Motors, of which the following is a specification.

My invention relates to a duplex motor and pump each being self-contained and independently attached upon a common base, whereby alternate mounting of 10 motor or pump is permissible, likewise permitting a change of pump of larger or smaller capacity without disturbing the position of motor or base, rendering all the parts interchangeable.

Another object of my invention relates to the construction of the motor, pump and base so as to insure perfect alinement of the parts in assembling, all being of universal construction eliminating the adjustments of a particular motor or pump to a particular base.

Another object of my invention is to provide the motor valves with cup-shaped packings mounted in their peculiar manner, forming a balanced valve, insuring free movement of the valve without any lateral strains.

Another object of my invention relates to the construction of the pump air chamber, enabling the pipe connection between the pump and governor to be made in a convenient and readily detachable manner.

Another object of my invention is to construct valve cylinder linings with ports through which the driving fluid is directed by the movement of the valves.

30 Various other features of my invention are more fully set forth in the description of the accompanying drawings, forming a part of this specification, in which:—

Figure 1 is a vertical sectional view through one of the motor cylinders and valves, one pump cylinder and air chamber, and through the governor. Fig. 2 is a perspective view of one of the valve cylinder linings. Fig. 3 is an enlarged central horizontal section through motor valve and cylinders. Fig. 4 is a central horizontal section through motor pistons and their contained cylinders. Fig. 5 is a section on line *x*, *x*, Fig. 1. Fig. 6 is a top plan view of the motor chests. Fig. 7 is a top plan view of the distributing chests located between the valve chests and piston chests. Fig. 8 is a section on line *w*, *w*, Fig. 1. Fig. 9 is a section on line *y*, *y*, Fig. 1. Fig. 10 is a section on line *z*, *z*, Fig. 1. Fig. 11 is a section on line *v*, *v*, Fig. 1, with the base omitted. Fig. 12 is a top plan view of the base. Fig. 13 is a section on line *a*, *a*, Fig. 12. Fig. 14 is a section on line *b*, *b*, Fig. 1. Fig. 15 is a section on line *c*, *c*, Fig. 14. Fig. 16 is a bottom plan view of the air chamber of the pump.

The valve and piston rod connections, and the distributing chest for so directing the energizing fluid that the right hand piston controls the left hand valve, and vice versa, are fully described in an application filed by

me September 19th, 1905, Serial No. 279,193. Likewise the governor herein shown controlling the fluid pressure to the motor and in connection with the pump pressure for automatic control thereof, is fully described in Patent No. 813,008, issued to me dated February 20, 60 1906.

The herein shown combined motor and pump, together with its automatic control are primarily adapted for household purposes, in which the fluid pressure is water in connection with the city mains for operating 65 the motor, and the pump is in connection with a cistern for pumping the cistern water through the house supply pipes. It is therefore desirable that the construction be of such character as to be simple, and effective, with but few working parts and compactly arranged as the outfit is usually in the hands of mechanically inexperienced persons.

The device is automatic in its operation, it being at rest for a period of time and operating when the supply is being used, it is therefore essential that the workings 75 of the device be positive in order to make the same available. Further the cost of construction must be such as to make the machine salable.

1 represents the base upon which the motor and pump are mounted, (see Figs. 12 and 13). This base is of 80 dish-formation for catching the drippings from the motor and pump, and is provided with an outlet 2, to which a drainage pipe may be attached.

3, 4, represent upwardly projecting flange supports upon which the motor and pump rest, provided with 85 the openings 5, 6, through which the pipe connections to the base of the motor and pump pass. These supports 3, 4, are identical in dimensions, in the same alinement and project above the marginal rim 7 of the base. This enables a series of bases to be finished in one operation and effecting proper alinement in mounting the motor and pump.

8 represents the motor chest, and being of duplex form is provided with the pistons 9, 10.

11, 12 represent duplex cylinders in the motor chest. 95 13, 14 represent piston rods secured to the pistons 9, 10, respectively.

15, 16, represent stuffing box nuts secured within a bore in the motor chest head and from the exterior thereof, and 15^a, 16^a, represent stuffing box nuts secured 100 from the interior of the motor chest opposite the nuts 15 and 16, forming a packing space between each other. The interior nuts form an abutment for cushioning the piston stroke, to be more fully hereinafter described.

17, 18, represent the outside cylinder heads preferably screw threaded into the motor chest for gaining access to the interior of the cylinder.

The pistons 9, 10, are preferably constructed as follows, (see Fig. 1). 19 represents a partition disk between the cup packings 20, 21, and held in position 110

upon the piston rod by means of a disk 22, and the nut disk 23 screw threaded on the piston rod. The disk 22 is provided with the flanged projection 26 forming a socket around the piston rod into which is fitted a rubber cushion 27, adapted to contact with the nut 15^a in the forward travel of the piston, serving to cushion the piston at the limit of the forward stroke. It is obvious that this construction of cushioning may be reversed, the cushion 27 being seated in the nut 15^a with equal effective results.

The motor chest is provided with inlet and exhaust ports, hereinafter to be described.

28 represents a distributing chest provided with a series of ports and passages, and which chest is secured 15 upon the motor chest the ports communicating with the valve ports of the valve chest above and with the ports of the motor chest below.

29 represents the valve chest secured upon the distributing chest 28, which valve chest is provided with 20 a series of ports and passages.

30, 31 represent cylinder linings forming the piston valve cylinders within the valve chest, (see Fig. 3).

32, 33, represent piston valves adapted to slide within the cylinders 30, 31.

25 34, 35, represent valve rods in connection with the pistons 32, 33.

36, 37, represent valve rod stuffing box nuts and 38, 39, represent valve cap screws threaded into the valve chest for gaining access to the interior of said valve chest.

The valve pistons are constructed as follows, and in this description I will only describe one, the other being a duplicate of the same. 40 represents a sleeve adapted to slide upon its valve rod, said sleeve being 35 provided with the flanges 41, 42, forming seats for the cup packings 43, 44, which are cupped inward, the function of which will be directly described. 45, 46, represent knurled screw threaded upon the sleeve for holding the packing in position. The free end of the 40 valve rod is screw threaded and provided with a nut 47, adapted to be adjusted to provide a determined amount of lost motion in valve movement at each limit of valve reciprocation, thereby allowing the various ports controlled by the valve, to remain in their open or 45 closed position to effect proper motor piston movements. With the valves constructed as shown it will be seen that the fluid pressure is controlled between the cup packings, thereby forming a balanced valve circumferentially, rendering a free movement of the 50 valves and causing a uniform wear on the peripheries of the packings. The inward pressure against the cup packings cause their flanged peripheries to expand outward against the cylinders, thereby assuring circumferential contact with the cylinders preventing leakage, 55 and so lengthening the life of the packing.

For a clear understanding of the operation of the motor as far as it is essential in this application, I will give a brief description of the various ports and passages controlled by the various valves in the operation of the 60 piston. Valve 32 controlling the movement of piston 10, and valve 33 controlling the movement of piston 9. 48 represents an inlet orifice common to both valves, (see Fig. 9), leading to the chamber 49 of the valve chest 29. The valve cylinder 31 is provided with an 65 annular series of orifices *a* opening into the chamber 49, and to impart a backward movement to piston 9, the fluid is driven through the following course. An open passage at such time being maintained from the fluid inlet chamber 49 to the piston 9, as follows:—

Through orifice *a*, valve passage formed between the 70 packing of the valve, through slots *a'*, into the chamber *a'*, through port *a'*, (see Fig. 10), passage *a'*, of the distributing chest 28 into the cross passage *a'* of the motor chest 8 through a port into the chamber *a'*, against the piston 9. The forward motion of the piston 9 is caused by the fluid being driven through the following course:—Through slots *b* in the valve cylinder 31, (it being understood that the piston 23 is in the opposite position from that which produces the backward movement of the piston 9), into chamber 80 *b'*, (see Fig. 11) formed in the valve chest 29, through port *b'* at the base of said chest, thence through passage *b'*, formed in the distributing chest 28, said passage being a cross-passage, and thence leading into passage *b'* of the motor chest through the ports *b'* of the distributing chest 28, thence into chamber *b'* at the forward end of the cylinder 11 and against the piston 9 driving the same forward.

The exhaust from cylinder 11 is accomplished as follows:— 50 represents an exhaust chamber formed in 90 the valve chest and at one end thereof, common to both valves. *d* and *d'* represent ports in the valve chest leading from the exhaust chamber 50 into the passages *d'* and *d'* of the distributing chest 28. (See Fig. 8). *d'* and *d'* represent ports in the motor chest 95 leading from the passages *d'*, *d'*, into the chamber 51 formed in the motor chest 8. 52 represents an exhaust chamber formed in the valve chest at the opposite end thereof from that of chamber 50, while *c*, *c'*, represent ports in the valve chest. *c'*, *c'*, represent passages 100 formed in the distributing chest 28, and *c'*, *c'*, represent ports in the motor chest 8, said ports and passages forming passages from exhaust chamber 52 into chamber 51 of the motor chest 8. Thus the exhaust when the piston 9 is in its forward movement will take the 105 following course:—From chamber *a'*, through cross passage *a'*, of the motor chest, passage *a'* of the distributing chest, port *a'*, chamber *a'*, valve chest slots *a'* of the valve cylinder into chamber 52 through ports *c*, *c'*, of the valve chest passages *c'*, *c'*, ports *c'*, *c'*, of 110 the motor chest into the chamber 51 thence through the final outlet passage 53, from whence it is carried off through suitable drainage. From chamber *b'* into passage *b'*, thence through ports *b'*, cross passages *b'*, port *b'*, chamber *b'*, thence through the slots *b'*, through 115 cylinder 31, into the chamber 50, through ports *d*, *d'*, passages *d'*, *d'*, ports *d'*, *d'*, into the chamber 51 and outlet 53. Of course it is to be understood, in said instance, that the valve 33 is in such forward position as to permit of a free passage from the slot *d'*, into chamber 120 52. The movement of valve 33 is obtained through the action of piston 9, while valve 32 receives its motion through the reciprocation of piston 10. The opposite valve and piston movements are obtained through the following course:—When fluid pressure is admitted 125 from chamber 49, through orifice *h*, through valve passage formed between the piston of valve 32, through slots *h'*, chamber *h'*, port *h'*, passage *h'* of the distributing chest, ports *h'*, and chamber *h'* in the motor chest, a rearward motion is imparted to piston 10. When 130

the fluid pressure is admitted from chamber 49, through orifice h through the valve passage of valve 32, through orifices or slots k , chamber k' , port k^2 , passage k^3 , and port k^5 of the motor chest into chamber k^6 , a forward motion is imparted to piston 10. The exhaust of cylinder 12 during the forward movement of piston 10, is as follows:—From chamber k^8 of the motor chest, port k^6 , and passage k^5 , of the distributing chest, thence through port k^4 , chamber k^3 of the valve chest, slot k^2 of the cylinder 30, thence through ports d , d^1 , passages d^2 , d^3 , and ports d^4 , d^5 , into the chamber 51 and outlet 53. The exhaust course when the piston 10 is moving in the opposite direction, is as follows:—From chamber k^6 , through port k^3 of the motor chest, thence through passage k^3 of the distributing chest, into chamber k^4 ; through port k^2 , thence through slot k and cylinder 30 into chamber 52, thence through port c , c' , of the valve chest, passages c^2 , c^3 , of the distributing chest and port c^4 , c^5 , of the motor chest, into the chamber 51 and thence through outlet 53.

The means employed for operating the valves 32, 33, consist of the following instrumentalities:—54, 55, represent actuating bars fixed to move with the piston rods 13, 14, respectively, to which they are secured, 25 they project downwardly and are held in vertical alignment, by the guides 56, 57, formed integral with the base 1. 58 represents a pin fixed to bar 54. 59 represents a lever pivotally supported upon a shaft 60, fixed within the sleeve 61 of the bracket arm 62 projecting 30 from the distributing chest 28, one end of the lever 59 being provided with a slot 62 (see Fig. 1), through which the pin 58 projects, the opposite end of the lever 59 being pivotally connected to a piston connecting link 63, said link being connected to the piston rod 24, 35 thus a forward movement of the piston rod 13 will cause a backward movement of the valve rod 34 and vice versa. The piston rod 14 is similarly connected with the valve rod 35. 64 represents a pin fixed to bar 55 and riding in a slot in the lever 65, pivotally supported upon the shaft 60. 66 represents a connecting link, having pivotal engagement with the lever 65 and valve rod 35 for actuating the rod 35.

The construction of the pump is as follows:—67 represents the piston chest provided with duplex cylinders 70, 71, within which the pistons 72, 73, slide respectively and being in connection with the piston rods 13, 14, of the motor. These pistons are of similar construction as the pistons of the motor, and provided with similar cushioning devices 74, adapted to contact 50 with the stuffing box nuts. 75 represents an inlet chamber to which the inlet pipe 76 is connected. 77 represents a series of valves controlling a series of ports leading into the chamber 75 and opening respectively into the forward and rear chambers 78, 79, of each cylinder of the piston chest. 80 represents valves controlling ports formed by the plate 81, fixed above the piston chest, and above the valves 77 and leading into the air chamber 82 from the chambers 78, 79. 83 represents stops formed on the shell 84 of the air chamber 60 for limiting the upward movement of the valves 80.

Each piston in the construction shown is double acting, that is, drawing water from the chamber 75 into the chamber 79, in the forward and reverse movement of the piston, that is, when the piston moves forward it is drawing water from chamber 70 into the

passage 78 and forcing the same through passages 79 into chamber 82, lifting valve 80, and through outlet passage 55. The rearward action drawing water from chamber 70 into chamber 79, and forcing the water from chamber 78 into the chamber 82 and out into the service passage 86. These passages 85 and 86 being connected to a suitable tank under pressure, which pressure in such tank controls the working of the governor, hereinafter to be described.

87 represents a downwardly projecting boss from the central portion of the shell 84, provided with a bore 88. This boss projects below the water line of the air chamber of the pump and the bore forms a passage for the water under pressure to be carried through the pipe 89 to the governor 90. Thus as the pressure from pipe 89 is exerted against the piston 91, and when it becomes greater than the pressure of the water in passage 92, forming the motor supply, and the combined spring tension against the piston 91, it will close the port 93, by means of the valve 94 in connection with the piston 91, seating upon the seat of the passage 93, and as the pressure against the piston 91 becomes less than the motor service pressure, the combined action of the water pressure through passage 92 and spring will cause the piston to move in the opposite direction, opening 90 the port 93 for starting the motor and pump. Thus an automatic control of motor and pump and storage tank supply is maintained.

95 represents a connecting rod connected with motor and pump.

Certain features disclosed in this application are not claimed herein, but are claimed in my copending application Serial No. 279,193, filed September 19, 1905.

Having described my invention, I claim:—

1. In a combined duplex motor and pump of the class described, the combination with a base of independent motor and pump supports, formed integral with said base projecting above the marginal edges of the base and in alignment with each other, and openings in said supports through which the motor and pump connections pass, substantially as described.

2. In a combined duplex motor and pump of the class described, the combination with a dish shaped base, of duplicate motor and pump supports, formed integral with said base projecting in a curved line on each side thereof above the marginal edges of the base and in central alignment with each other, openings in said supports through which the motor and pump connections pass, substantially as described.

3. A support for a combined motor and pump of the class described, composed of a base provided with duplex elevated pedestals formed integral therewith, in central alignment and adapted to be selectively used as pump or motor supports, substantially as described.

4. In a combined duplex motor and pump of the class described, in combination with a dish shaped base motor and pump supports, formed integral with said base projecting above the marginal edges of the base and aligned with each other, substantially as described.

5. In a combined duplex motor and pump of the class described, in combination with a dish shaped base, motor and pump supports formed integral with said base, projecting above the marginal edges of the base, openings in said supports through which the motor and pump connections pass, substantially as described.

6. In a combined duplex motor and pump of the class described, in combination with a dish shaped base, motor and pump supports formed integral with said base, projecting above the marginal edges of the base and aligned with each other, an opening in said base for permitting drainage thereof, substantially as described.

7. In a duplex motor and pump of the class described, a self-contained motor, a self-contained pump, having a common piston rod in connection with a base, provided with motor and pump supports of duplicate construction and alignment, whereby the motor and pump may be interchangeably mounted upon said supports, substantially as described. 50
8. In a duplex motor and pump of the class described, a self-contained motor, a self-contained pump having a common piston rod in combination with a base, provided with motor and pump supports of duplicate construction and alignment, whereby the motor and pump may be interchangeably mounted upon said supports, and a tie-rod connecting the motor with the pump, substantially as described. 55
9. In a duplex motor and pump of the class described, a motor piston chest, a pump piston chest in alignment with each other, duplex pump pistons and duplex motor pistons each provided with cushioning means, duplex piston rods 20 connected with motor and pump pistons, a central bore in the head of both motor-piston chest and pump piston chest in alignment with each other, stuffing box nuts inserted from each side into the said bores, the inner nut in each instance forming an abutment against which the cushioning means of the pistons contact, the parts being so arranged that the motor pistons effect a cushioning of stroke in the forward movement of the piston rods, the pump pistons acting in the reverse movement, substantially as described. 60
10. In a duplex motor and pump of the class described, a motor piston chest, a pump piston chest in alignment with each other, duplex motor and pump pistons, duplex piston rods connecting one motor piston with its opposite pump piston, central bores in the heads of both motor and pump chests through which rods pass, stuffing box nuts inserted from each side into the said bores forming a central packing chamber, cushioning means arranged between the pistons and inner stuffing box nuts whereby the pistons are cushioned at each limit of forward and reverse stroke, substantially as described. 65
11. In a duplex motor and pump of the class described, a valve chest provided with ports and passages, a motor chest provided with ports and passages, a distributing chest provided with ports and cross passages arranged between the valve and motor chests, duplex valve cylinder linings provided with fluid passages leading into the chest 70
